UNITED STATES PATENT OFFICE.

JAMES A. BRENT, OF NEW YORK, N. Y., ASSIGNOR TO THE BRENT COMPANY, INC., A CORPORATION OF NEW YORK.

TENT-SUPPORTER.

1,202,475.

Specification of Letters Patent. Patented Oct. 24, 1916.

Application filed January 24, 1913. Serial No. 743,962.

To all whom it may concern:

Be it known that I, JAMES A. BRENT, a citizen of the United States, residing at New York, in the State of New York, have 5 invented certain new and useful Improvements in Tent-Supporters; and I do hereby declare the following to be a full, clear, and exact description of the invention, such as will enable others skilled in the art to which

10 it appertains to make and use the same.

The present invention relates to the provision of means for quickly and effectively raising and supporting tents of all kinds, without the use of special devices permanently incorporated in the tents themselves, 15 and without the use of openings of any kind to accommodate the supporting means.

The principal object of this invention is to supply light, portable, inexpensive and 20 easily operated means for carrying out the ends above mentioned, whereby the labor of pitching tents and the convenience of this operation are greatly enhanced.

I have illustrated certain preferred embodiments and applications of this invention in the accompanying drawings, where- 25 in—

Figure 1 is a longitudinal section of one form of supporter applied to a fabric of 30 any kind, Fig. 2 is a cross section of the same through the middle, Fig. 3 is a similar view near one end, Fig. 4 shows one means for employing a pair of these supporters, Fig. 5 shows one mode of applying the de- 35 vice to one form of tent, Fig. 6 shows another mode of applying the device to tents, and Fig. 7 is a cross section of a modified form of external frame.

I employ an external frame 10, which 40 may be of wood, metal, wire, or other material that is suitable, and within this frame I use a core 11, preferably in the form of a bar, but not necessarily. Combined with these elements I employ means for creating 45 mutual pressure between the frame and its contents. The frame 10 may have various shapes, as indicated by two examples of cross sections shown in Figs. 3 and 7.

In Fig. 1 the frame is practically a trough-shaped box. The core is a bar 11, with enlarged ends 12. The means for creating pressure as aforesaid is the pressure-plate 13, having a guiding lip 14, and adapted to be pushed in and out by the screw 15,

threaded into one end of the box and so secured to the plate 13 as to draw or push it out or in, while still capable of turning.

Various means for exterior attachment of the frame may be used. For instance, eyes 16 may be placed at one or both ends of the 60 frame, as in Fig. 1, or a single stout eye 17 may be used on top of the frame, as in Fig. 4.

For the sake of lightness, where a wire framework is not used, the box 10 is cut out 65 at intervals in a more or less ornamental manner, as shown at 18. I also prefer to roughen the internal contact surfaces at the ends as shown in Figs. 1 and 3.

In applying the device to a given fabric, 70 the frame 10 is applied to the upper side thereof with the pressure device in retracted position. The core is then placed under the fabric and pushed up into the frame forcing the material over it up into the frame as 75 shown at 19 in Figs. 1 and 2. When this is accomplished the pressure device is tightened, and, in the form shown, this is done by appropriate action of the screw 15. This creates pressure against the ends of the 80 core, and firmly secures the whole in place. I also prefer slightly to incline the ends of the frame 10 toward the opening, as shown, in order to narrow said opening, and thus increase the security of the device.

In Fig. 5 is shown a means for applying the device to a conical tent 20. The apex of the tent having been secured within the supporter in the manner already described, a rope 21 may be strung through the supporting eye 17 at the top, and its ends secured to suitable props, such as the tree 22 and the pole 23, the latter being supported by a stay rope or wire, 24. The top being thus held up, the edges are staked down in any usual 95 manner as at 25.

In Fig. 6 is shown a preferred means for pitching a wall tent, with A shaped roof. One advantage of my invention in this connection lies in the fact that I am able to govern the degree of tension exerted along the ridge or apex line of the tent, while holding the canvas taut, along vertical lines.

As shown in Fig. 6, I prefer to apply a separate fabric supporter 10 to each end of 105 the ridge line, and to suspend these supporters by cords or ropes 26, 27, at their outer edges, with a tension rope 28 connecting the

two supporters. In this case the supporters are preferably of the form shown in Fig. 1, with eyes at their ends. The ropes 26 and 27 are somewhat inclined so as to permit 5 raising and lowering of the whole; and, by suitable adjustments of the rope 28, the tension can be entirely taken off of the ridge line of the tent, as indicated by the loose condition shown in Fig. 6, or such tension may 10 be relieved to any less extent.

Another mode of employing this invention for supporting fabrics under conditions permitting adjustment of tension is shown in Fig. 4. Here the supporters proper are 15 fixed to two bars 29, 30, which telescope into a sleeve 31. The tension can be adjusted by sliding the bars nearer together or farther apart and securing them by means of set screws 32, or other means for adjusting the 20 bars and securing them may be used. By raising the sleeve 31 and its bars by means of a rope 33, or otherwise, the tent may be quickly pitched.

Various changes may be made in my 25 device without departing from the scope of my invention, and I do not limit myself to the details herein shown and described.

What I claim is—

1. Means for supporting a tent comprising in combination two separate devices for 30 gripping the canvas from without, tensional supports attached to said devices tending to draw them apart and an adjustable tension device connecting said gripping devices, whereby the tension exerted on the canvas 35 may be regulated and be made independent of the degree of tension exerted by said supports.

2. Means for supporting a tent comprising in combination two separate devices for 40 gripping the canvas from without, tensional supports attached to said devices tending to draw them apart and an adjustable rope connecting the said gripping devices outside of the tent, whereby the tension exerted 45 upon the canvas by the supports may be regulated.

In testimony whereof, I affix my signature, in presence of two witnesses.

JAMES A. BRENT.
